UNITED STATES PATENT OFFICE.

EDWARD C. TAUBEL, OF NORRISTOWN, PENNSYLVANIA.

KNITTED FABRIC.

Application filed August 28, 1922, Serial No. 584,822. Renewed May 19, 1924.

To all whom it may concern:

Be it known that I, EDWARD C. TAUBEL, a citizen of the United States, residing at Norristown, in the county of Montgomery and State of Pennsylvania, have invented certain new and useful Improvements in Knitted Fabrics, of which the following is a full, clear and exact specification.

This invention relates to knitted fabrics, 10 and especially to those from which seamless hosiery or stockings are made.

When such hosiery are made on the ordinary circular knitting machines no lines or demarcations appear down the backs of the 15 stockings, and the seamless hosiery may be easily distinguished from the full-fashioned hosiery in that way, the full-fashioned hosiery having seams down the back where the edges of the fabric, which is knitted 20 on a flat machine, are sewed together. The trade has come to demand some kind of seam or mock seam on seamless hosiery to simulate full-fashioned hosiery, and some manufacturers have resorted to the expedient of running a line of stitches down 25 the back of each seamless stocking after it comes from the knitting machine.

It is the object of the present invention to provide a fabric having a line or demarcation formed therein during the knitting thereof on a circular machine, said line or demarcation being located down the back of the stocking or at any other desired point. By incorporating said line or demarcation in the fabric during the knitting thereof, the time and expense of forming 35 a mock seam in each stocking as a separate operation is saved, and at the same time the stocking is made thicker and more durable 40 down the back, as well as attractive to the eye and distinctive in appearance.

Another feature of full-fashioned hosiery which distinguishes it from seamless hosiery is the line of dots or points which 45 appear along either side of the seam where the stitches are dropped on the flat knitting machines in fashioning the fabric to conform to the curve of the leg above the ankle, and it is a further object of the present invention to provide a seamless fabric for stockings having a similar line of dots or points at either side of the line of demarcation down the back of the stocking, said line 50 of dots or points being also formed during the knitting of the fabric on a circular machine.

The invention will be first hereinafter described in connection with the accompanying drawings, which constitute part of this specification, and then more specifically defined in the claims at the end of the description.

In the accompanying drawings, wherein similar reference characters are used to designate corresponding parts throughout the several views:—

Figure 1 is a rear perspective view of a stocking formed of seamless fabric in accordance with this invention.

Figure 2 is an enlarged outside view of a portion of the fabric across the back line or stripe thereof.

Figure 3 is an inside view of a similar portion of the fabric drawn to the same scale as Figure 2, with the long strands of the extra threads broken away in the upper portion but shown in place in the lower portion thereof in order to show the courses of said extra threads more clearly.

Figure 4 is a section on the line IV—IV of Figure 3, showing the full courses of the extra threads, and also the crimps or raised areas formed at intervals in the stripe by drawing three adjacent threads together and increasing the tension on the intermediate thread of the group, and

Figure 5 is a view similar to Figure 2, showing a portion of the fabric at one side of the stripe where one of the dots or points is formed.

The stocking fabric is knit on a circular machine, and during the knitting process the stripe 2 and the lines of dots or points 3 at either side of said stripe are formed in said fabric so that the finished stocking will have the appearance shown at 1 in Figure 1. Said dots or points 3 are formed in the main fabric 4 by drawing together three of the threads, as at 5, Figure 5, at desired intervals parallel to the stripe 2.

Said stripe 2 is formed by introducing an extra series of threads 6, see Figures 2, 3 and 4, into the fabric over so much of the area thereof as it is desired that said stripe should extend. As shown in the drawings, the main stripe consists of four similar subsidiary stripes 7 arranged side by side and of the same width, but it will be understood that the number of said subsidiary stripes may be varied and the width of the same also changed as may be desired without departing from the present invention.

The threads 8 of the main fabric 4 are each formed into a row of upwardly extending loops 9 interengaging with the next thread above, and a row of downwardly extending loops 10 interengaging with the next thread below, the upwardly extending loops 9 of all the threads being vertically alined with each other in the main fabric, and the downwardly extending loops 10 of all the threads being also arranged in vertical alinement with each other. The extra threads 6 are introduced into the fabric along with the threads 8 of the main fabric throughout the extent of the stripe 2, but said extra threads have fewer loops than the main fabric threads. The upwardly extending loops 11 of the extra threads 6 span a plurality of the upwardly extending loops 9 of the main fabric threads, while the downwardly extending loops 12 of said extra threads follow the downwardly extending loops 10 of the main fabric at spaced intervals, said downwardly extending loops 12 appearing on the outside of the fabric in vertical rows indicated by the parallel lines 13 in Figure 1, while the upwardly extending loops 11 of greater lateral extent lie on the inside of the fabric. The extra threads also have long strands 14 extending across the full width of the stripe 2 on the inner face of the fabric, as best shown in Figure 4, said long strands 14 connecting the last of the downwardly extending loops 12 on opposite margins of the stripe.

Crimps or raised areas 15 are formed at intervals in the subsidiary stripes 7 by drawing together three adjacent threads 6 and 8 in line with the downwardly extending loops of the extra threads 8, after the same manner as the dots or points 3 are formed in the main fabric; and by increasing the tension on the intermediate thread of each such group of three, so as to cause the puckering of the fabric on the outside as shown in Figure 4. The upwardly extending loops 11 of the extra threads of the groups of three are arranged substantially as indicated in Figure 3, the top and bottom ones in each group being arched upward as at 16 under the raised areas 15, while the intermediate one of each group is drawn taut by the increased tension thereon, so as to bind said arched portions 16 of the other loops 11 in place and support the puckered or raised areas 15. It will be understood that the spacing between the said raised areas or crimps 15 in the subsidiary stripes 7 may be varied as may be desired. The lengths of the lines of dots or points 3 may also be varied with respect to the stripe 2, and other changes in details may be made without departing from the spirit or sacrificing the advantages of this invention. I, therefore, reserve the right to make such changes in the invention herein illus-

trated and described as fairly fall within the scope of the appended claims.

I claim:

1. A knitted fabric of the character described having a stripe formed in the knitting from additional threads, and a series of raised areas spaced apart at intervals longitudinally of said stripe and formed by drawing together groups of said additional threads with corresponding threads of the main fabric, certain of the additional threads of said groups having greater tension than the others, while the additional stripe-forming threads in the spaces between said raised areas follow the same courses and have the same tension as the corresponding threads of the main fabric. 75

2. A knitted fabric of the character described having a stripe formed in the knitting from additional threads, and raised areas on said stripe formed by drawing together groups of three of said additional threads with corresponding threads of the main fabric, the upper and lower threads of each group being drawn into line with the intermediate threads thereof, and the intermediate additional thread of each group having greater tension than the other threads of said groups. 85

3. A knitted fabric of the character described having a stripe formed in the knitting from additional threads, and raised areas on said stripe formed by drawing together groups of said additional threads with corresponding threads of the main fabric, certain of the additional threads of said groups having greater tension than the others, and said other additional threads in said groups being arched between said more greatly tensioned additional threads and the threads of the main fabric. 95

4. A knitted fabric of the character described having a stripe formed in the knitting from additional threads, and raised areas on said stripe formed by drawing together groups of three of said additional threads with corresponding threads of the main fabric, the upper and lower threads of each group being drawn into line with the intermediate threads thereof, the intermediate additional thread of each group having greater tension than the other threads, and the other additional threads of each group being arched between said more greatly tensioned additional thread and the threads of the main fabric. 110

5. A knitted fabric of the character described having a stripe formed in the knitting from additional threads run in with the threads of the main fabric, said additional threads having short loops coinciding with certain loops of the threads of the main fabric, while other loops of said additional threads are long enough to span a plurality of the loops of the threads of the 120

main fabric, certain of the long loops of said additional threads having greater tension than the other long loops thereof, whereby raised areas of the main fabric are formed 5 in the stripe.

6. A knitted fabric of the character described having a stripe formed in the knitting from additional threads run in with the threads of the main fabric, said additional 10 threads having long loops spanning a plurality of the loops of the threads of the main fabric, and certain of said long loops of the additional threads having greater tension than the other long loops thereof, 15 whereby raised areas of the main fabric are formed in the stripe.

7. A knitted fabric of the character described having a stripe formed in the knitting from additional threads run in with the 20 threads of the main fabric, said additional threads having long loops spanning a plurality of the loops of the threads of the main fabric, certain of said long loops of the additional threads having greater tension than 25 the other long loops thereof and then the threads of the main fabric, whereby raised areas of the main fabric are formed in the stripe, and the other long loops of the additional threads at said raised areas being 30 arched between said more greatly tensioned additional threads and the raised areas of the main fabric.

8. A knitted fabric of the character described having a stripe formed in the knitting 35 from additional threads run in with the threads of the main fabric, groups of said additional threads and corresponding main-fabric threads being drawn together in groups, said additional threads having 40 long loops spanning a plurality of the loops

of the threads of the main fabric, and certain of said long loops of the additional threads having greater tension than the other long loops thereof, whereby raised areas of the main fabric are formed in the stripe. 45

9. A knitted fabric of the character described having a stripe formed in the knitting from additional threads run in with the threads of the main fabric, groups of said additional threads and corresponding main- 50 fabric threads being drawn together in groups, said additional threads having long loops spanning a plurality of the loops of the threads of the main fabric, and certain of said long loops of the additional threads 55 having greater tension than the other threads, whereby raised areas of the main fabric are formed in the stripe, the other long loops of the additional threads at said raised areas being arched between said more 60 greatly tensioned additional threads and the raised areas of the main fabric.

10. A knitted fabric of the character described having a stripe formed in the knitting from additional threads run in with the 65 threads of the main fabric, said additional threads each having short loops coinciding with certain loops of the threads of the main fabric and appearing on the outer face of the fabric, and each of said additional threads also having a plurality of long loops each spanning a plurality of the loops of the threads of the main fabric on the inner face of the fabric, one of said long loops of each additional thread being longer 70 than the other long loops thereof and spanning a plurality of the latter.

In testimony whereof I have signed my name to this specification.

EDWARD C. TAUBEL.
